UNITED STATES PATENT OFFICE

FRED A. ISAACSON AND KNUTE EDAHL, OF CHICAGO, ILLINOIS

CAR CONSTRUCTION

Application filed March 8, 1930. Serial No. 434,190.

Our invention relates more particularly to improvements in railroad refrigerator cars whereby a more moisture and weather-proof construction is provided.

5 Our invention also involves improvements whereby a moisture-proof construction is obtained and proper compensation for expansion of the inside lining of the car is provided, with the result that the cost of maintenance is materially reduced and longer car 10 service provided.

Another object of our invention is the provision of means whereby the floor-racks are hingedly secured in place so as to provide a 15 more rigid connection while at the same time providing sufficient play or movement in the hinge connection to take care of any unevenness in the floor proper so as not to place undue strains on the hinge attachment members, while at the same time holding the floor-racks in rigid position relative to the side walls of the car, without improper longitudinal or lateral motion.

20 The above enumerated objects, as well as other objects and advantages inherent in the construction, will all be fully comprehended from the following detailed description of the accompanying drawings, wherein:

25 Figure 1 is a cross-sectional view of a portion of the side wall and floor of our improved car construction.

30 Figure 2 is a detail cross-sectional view of a similar portion of the car, with portions of the construction shown in Figure 1 omitted.

35 Figure 3 is a cross-sectional view of the lower portion of the bulk-head of the car.

40 Figure 4 is a sectional elevation taken substantially on the line 4-4 of Figure 1, looking in the direction of the arrows.

45 Figure 5 is a sectional elevation of the car side wall adjacent the bulk-head and ice compartment.

50 Figure 6 is a perspective view of the lower portion and at one end of the bulk-head as viewed from the ice-box or compartment side.

In Figures 1 and 2 we illustrate the features of our invention which pertain more particularly to the main portion of a refrigerator car; the figures showing a portion of the

car side wall comprising the inner side wall or lining 10; various layers of suitable insulating material 11, all arranged in the manner usual in railroad refrigerator cars and held by the usual belt-rail 12 whereby the 55 outer wall or sheathing 13 is held in spaced relation with the insulation layers as shown in Figure 1; the belt-rail 12 providing means for nailing the inner lining 10 and the layers of insulation 11, in place as shown. 60

In refrigerator cars as heretofore constructed, the inner lining 10 was made to extend from a top or ceiling rail of the car to the floor, with the result that the inner lining boards, after absorbing a certain amount of moisture (due to packing shipments of vegetables and other commodities in ice) would bulge because no allowance was provided for expansion of the lining.

One feature of our invention consists in 70 the provision for such expansion, while at the same time providing means for securely holding the lining in place. In our improved construction, this inner lining 10 is terminated a distance above the car floor shown at 14. 75

The lower longitudinal sides of the bottom lining board 10 are firmly held in place by the specially constructed floor-rack hinge attaching or pivot providing plate or member 15, while at the same time allowing for expansion of the lining boards.

80 The attaching or pivot providing plate 15 is formed with a vertical rear wall 16 off-set outwardly at 17 (shown more clearly in Figure 2) so that the upper longitudinal part of the plates 15 may lap a portion of the lower lining element or board as shown and thereby secure the lower edge of the lining in place. The attaching plate 15 is preferably provided with a pair of bolt-holes which are disposed through the enlargements or bosses 18 located adjacent to the off-set 17. The plates 15 at bottom preferably have their rear walls curve forwardly into the base portion 19 and at an intermediate portion each have the vertically disposed web portion 20 which at top terminates in the hinge-pin receiving head 21. The hinge also involves a plate 22 which is adapted to be secured to the side stringer 23 of the adjacent floor-rack section partially shown at 100

24 in Figure 1 by bolts as at 25. The plate 22 is provided with the two upstanding lobes 26, 26 spaced apart so as to straddle the head 21 of attaching plate 15; the lobes 26, like head 21 being transversely apertured to receive the hinge-pin 27.

In order to compensate for any unevenness in the car-floor or between the floor and the floor-racks, we provide the head 21 of attaching plate 15 with a vertically arranged elliptic or oblong slot, as shown in dotted lines at 28 in Figure 1, to receive the hinge-pin 27. With this arrangement it is apparent that vertical movement of the hinge-pin is permitted so that the stringers of the floor-rack may at all times rest on the floor, instead of supporting the weight of the floor-rack and superposed merchandise on the hinge-pin as heretofore has been the case whereby improper strains were also transmitted to the car side wall.

The hinge attaching plate 15 is secured in place by suitable bolts 29 which pass through a stringer 30, disposed longitudinally of the car side-wall intermediate of the side-door openings and the car end walls, through the layers of insulation 11 and through the apertured bosses 18 of the hinge-plate 15. The stringer 30 is preferably provided with a groove or countersunk opening at 31, to receive the head of bolt 29; while the inner longitudinal side of the stringer is grooved to receive the flanged end of a metallic spacer or ferrule 32, as shown at 33 in Figure 1. The bolt 29 is inserted as shown and described so that its threaded end will extend through the apertured bosses 18 of plate 15, where it is provided with a nut 34.

This permits a firm fastening of the hinge-plate 15 in place while at the same time permitting removal and renewal of the floor-rack hinges, should occasion require, without removal of the bolts and without in any way mutilating or disarranging the general side wall construction.

After the bolt 29 has been inserted through the stringer 30, the countersunk opening 31 is then filled with a suitable insulating material as indicated at 34^a and the outer side of the stringer 30 is then provided with a strip of insulating material 35 which is preferably nailed to the stringer. With this arrangement a temperature seal or proper insulated construction is provided.

As shown in Figure 1, the car inner lining 10 terminates at 36 back of the upper off-set wall of the hinge-plate 15; and the rear face of the bottom lining board is cut away or gained to fit over the upper longitudinal edge of an angular or L-shaped metallic member or plate 37 which extends along the bottom of the car inner side walls between the door-openings and the bulk-heads or end walls of the car proper. The member 37 consists preferably of a proper galvanized steel plate bent

longitudinally into shape so as to permit one side to extend vertically against the insulation 11, while the other longitudinal side extends over the floor 14 and beneath the foot portion 19 of the floor-rack hinge member 15.

Before installing the moisture shedding member or metallic plate 37, and before attaching the floor-rack hinges to the side walls, the juncture between the floor 14 and the side wall insulation 11 is provided with oakum, which is caulked in place, as shown at 38, and the space above the oakum then filled with a suitable water proofing compound, as shown at 39 which is troweled to proper contour. At the same time a layer of asphaltum or other suitable water proof material is applied as shown at 40. The shaped metallic plate 37 is then applied before the water-proofing compound and asphaltum have thoroughly dried so that the compound may be shaped to the plate 37 and provide a proper water seal rearward and beneath the plate 37 and about the bolts 41 which pass through the horizontal sides of the plates 37, through the floor 14, bottom layers of insulation 42, sub-floor 43 and the bottom side stringer 44. A suitable number of bolts 41 are employed throughout the length of the plate 37 so as to firmly draw the plates into place, thereby causing the water-proofing compound to ooze about the edges of the plate and about the bolts 41.

The bottom of the car is also provided with a suitable water-proofing compound beneath the floor 14 and the sub-layers of insulation, and the lower end of the side wall insulation is provided with a metallic flashing 45 extending at bottom beneath the inner layer of insulation and at top above the plane of the floor 14 rearward of angle plate 37.

It is understood, of course, that the flashing 45 is installed before the plate 37 and floor-rack hinge are put into place.

With this construction it is apparent that a moisture-proof relation between the car side walls and the car floor is provided whereby seepage of water into the juncture or crevice is made impossible. The vertically disposed sides of the plates 37 are firmly held in place by the hinge-plates 15 and the lower edges of the inner lining boards.

In order to provide proper temperature insulation, the bottom or floor stringer 44, secured on the side sill 46, is grooved or socketed as shown at 47 to receive the head of the bolts 41 and the socket then filled with a suitable insulating material.

At the ice compartment end of the car and extending beneath the bulk-head 48 is the usual splash-plate 49 (see Figures 5 and 6) arranged on the lateral flange of the drip-pan 50; the ice-box or compartment side of the car being also provided with the usual beveled bottom rail as shown at 51.

In order to provide a water-proof relation

about this bottom rail 51, we arrange a metallic flashing 52 rearward of and beneath the angle plate or metallic member 37 and provide the upwardly disposed portion 5 against the end of the bottom rail as shown at 52^a and the portion across the top of the rail, as shown at 52^b.

This metallic covering about the end of the bottom rail 51 is preferably a built-up structure composed of the strips 52^a and 52^b, which are soldered together and the edges which contact with the flashing 52 soldered thereto. In order to effect a moisture-proof relation, the flashing 52 is also preferably soldered to the side plate 37 and to the splash-plate 49, thus making it impossible for the water to come into contact with the wood and insulation elements of the car, as the ice chamber side of the bulk-head is also provided with a flashing as shown at 53.

We have described our improved car construction in terms employed merely as terms of description and not as terms of limitation, as structural modifications are possible and 25 may be made without, however, departing from the spirit of our invention.

What we claim is:

1. A refrigerator car construction wherein in the inner lighting terminates a distance 30 above the car-floor; an angular metallic plate disposed along the car sides, with one longitudinal side of the plate arranged rearward of the lower longitudinal edge of the car lining, while the other longitudinal side 35 of said plate extends parallel with the floor; moisture-proof material intermediate of said plate and the floor and the side wall insulation of the car; and means whereby said plate is secured in place.

40 2. A refrigerator car construction provided with insulated walls and an inner sheathing or lining boards, the lining boards terminating a distance above the car-floor; a metallic plate of L-shape cross-section arranged lengthwise of the car sides, with one side of the plate against the side wall insulation and rearward of the lower lining board, while the other side extends parallel with the floor and is secured thereto; water- 45 proof material intermediate of the plate, the side wall insulation and the floor; and means whereby the lower lining board is clamped in place so as to permit vertical expansion.

55 3. A refrigerator car provided with insulated walls and inside lining boards, the lining boards terminating a distance above the car-floor and the lower lining board being gained on its rear face; a metallic plate of L-shape cross-section arranged lengthwise of the car sides with one side of the plate at its upper longitudinal edge disposed in the gain of the lower lining board, while the other side of said plate extends along the floor; moisture-proof material rearward of 60 and beneath said plate; a floor-rack attach- 65

ing member having a vertical wall arranged flush with the vertical side of said plate, said vertical wall being off-set and said off-set portion arranged in lapping relation with the lower lining board; means disposed through said attaching member and said plate whereby said member and plate are secured to the car side wall; and means disposed through said plate and the car floor for securing the lower longitudinal side of said plate in place.

70 4. In a refrigerator car provided with a floor-rack and inside lining boards; a metallic plate L-shaped in cross-section disposed lengthwise of the car with one longitudinal side lapping the car side rearward of the lining board while the other longitudinal side is disposed on the car-floor; floor-rack attaching members arranged on said plate and each provided with a base portion and a vertical rear wall arranged flush with said plate beneath the lower lining board and off-set beneath its upper edge so as to permit said upper edge to lap the outer face of the lower lining board; said member being provided with a hinge-pin carrying head having a vertically elongated opening for said pin; a longitudinal stringer intermediate of the inner and outer walls of the car; and bolts arranged in said stringer whereby 80 said attaching member and the vertical side of said plate are rigidly secured in place.

85 5. A refrigerator car construction involving spaced outer and inner walls and insulating material arranged therebetween; the inner wall terminating a distance above the car-floor; a metallic plate of L-shape cross-section arranged lengthwise of the car at the juncture of the side walls and the floor on the car interior with the vertical side of the plate disposed rearward of the lower side wall lining board; a floor-rack attaching member seated on said plate and provided with an off-set vertical wall arranged in lapping relation with the lower lining board; a stringer arranged lengthwise of the car intermediate of the outer side wall and the insulating material; metallic spacers intermediate of the vertical side of said plate and said stringer and disposed through said insulating material; and bolts arranged in said stringer and disposed through said spacers, said plate and said attaching member whereby the latter and said plate are secured in place.

100 6. A refrigerator car involving spaced outer and inner walls with insulating material therebetween; the inner wall boards terminating a distance above the car-floor; a stringer disposed lengthwise of the car intermediate of the outer wall and the insulating material; a metallic plate of L-shape cross-section arranged lengthwise of the juncture of the car side walls and the floor, with one side of the plate arranged against said in- 105 110 115 120 125 130

5 insulating material and rearward of the inner car wall while the other side is arranged on the car-floor; spacer members disposed through said insulating material intermediate of the stringer and said plate; floor-rack 10 attaching members seated on said plate and provided with off-set vertical walls adapted to lap the lower portion of the inner car wall and clamp the same in place; bolts carried by said stringer and disposed through said spacer members and the attaching members whereby the latter are removably secured in place; the heads of said bolts being countersunk in said stringer; and insulating material 15 secured to the outer face of said stringer and in the countersunk openings of the stringer.

7. A refrigerator car having spaced outer and inner walls and sheets of insulating material therebetween; the inner wall terminating a distance above the car-floor; a plastic moisture-proof compound between the floor and the car side walls; a metallic plate of L-shape cross-section arranged along the car sides and disposed on said plastic compound 20 in lapping relation with the car-floor and said sheets of insulating material with the upper longitudinal edge of the plate arranged rearward of the bottom portion of the inner wall; bolt-carrying stringers disposed lengthwise 25 of the car side walls intermediate of the outer wall and the sheets of insulating material and in insulated relation with the outer wall; and floor-rack attaching members seated on said plate and provided with off-set walls 30 adapted to overlap the lower portion of the inner wall so as to clamp the latter in place while permitting vertical expansion of said inner wall; said attaching members being secured in place by the bolts carried by said stringers.

40 8. A refrigerator car provided with an inner lining and with a bulk-head provided with a bottom rail; a metallic plate of angular cross-section arranged along the car sides and the adjacent portion of the car-floor, with the vertical side disposed rearward of the inner lining; a metallic flashing rearward of said plate at the bulk-head end, said flashing having portions arranged in lapping relation 45 with the sides and ends of said bottom rail, with the junctures between the flashing and said plate integrally secured together into moisture-proof relation; with means whereby said plate and the flashing are removably secured in place.

55 9. A refrigerator car provided with an inner lining, floor-racks, a bulk-head provided with a bottom rail and a splash-plate; a metallic plate of angular cross-section arranged along the car sides and the adjacent portion of the car-floor, with the vertical side disposed rearward of the inner lining which terminates above the car-floor and is arranged to permit expansion; a metallic flashing rearward of said plate at the bulk-head 60

65 end, said flashing having portions arranged across the top, sides and ends of said bottom rail, with the junctures between the flashing, said plate and the splash-plate all integrally secured together into moisture-proof relation; means whereby said plate and flashing are secured in place; and means located on the plate adjacent to the car sides and in lapping relation with the lower part of the car lining whereby the latter is yieldingly held in place, said means also constituting means for pivotally connecting the floor-racks in place.
